UNITED STATES PATENT OFFICE.

WILLIAM JORDAN AND CHARLES S. NICHOLS, OF LANCASTER, NEBRASKA.

AEROPLANE.

Application filed October 31, 1927. Serial No. 230,085.

This invention relates to improvements in aeroplanes and has for an important object thereof the provision of auxiliary pivoted planes which may be shifted to check the motion of the aeroplane to enable landing upon their respective surfaces.

Another object of the invention resides in the provision of an auxiliary plane of this character which when in use has means for 10 braking the aeroplane and will not tend to make the same nose downwardly.

A still further important object of the invention resides in the provision of an improved aeroplane of this nature which is exceedingly simple in construction, easy to operate, fairly efficient and reliable in use and 15 operation, and otherwise well adapted to the purpose for which it is designed.

With the above and numerous other objects 20 in view, as will appear as the description proceeds, the invention resides in certain novel features of construction, and in the combination and arrangement of parts as will be hereinafter more fully described and claimed.

25 In the drawings:

Figure 1 is a side elevation of an aeroplane embodying the features of my invention,

Figure 2 is a fragmentary sectional view taken substantially on the line 2—2 of Figure 1; and

Figure 3 is a fragmentary longitudinal vertical section taken substantially on the line 3—3 of Figure 2.

Referring to the drawing in detail, it will 35 be seen that the numeral 10 indicates the fuselage of the aeroplane, the numeral 11 the planes thereof. While in all instances the aeroplane has been illustrated as being of the bi-plane type, it will hereinafter become apparent that the principal construction employed with my auxiliary plane may be applied to monoplanes or any of the multiple plane types with the same result.

In accordance with my invention, in the 40 present example, the lower plane 12 has a shaft journaled in forward struts 13 so as to lie along the forward edge of the bottom plane. Auxiliary planes 14 are fixed to the shaft 12 and normally extend rearwardly on top of the plane 11. A crank 15 is attached to the shaft 12 in the fuselage 10 as illustrated to advantage in Figure 3. A lever 16 is pivotally mounted in the fuselage in any pre-

ferred manner and has a link 17 projecting therefrom and engaged with the crank 15. In 55 the present instance it will be seen that the lever 16 may be pushed forwardly so as to raise the rear edge of the auxiliary planes 14 upwardly with the dotted line position shown in Figure 3 so that these auxiliary planes will 60 function as brakes to retard the aeroplane so as to allow the same to land in a restricted area. It will be seen by having the auxiliary planes hingedly mounted at their forward edges to the forward edges of the planes of 65 the aeroplane that nosing of the aeroplane is prevented because these auxiliary braking planes create a resistance which would tend to lift the nose of the fuselage.

It is thought that the construction, operation and advantages of this invention will 70 now be quite apparent to those skilled in this art without a more detail description thereof. The present embodiment of the invention has been disclosed in detail merely by way of 75 example since in actual practice it attains the features of advantage enumerated as desirable in the statement of the invention and the above description. It is apparent that 80 changes in the details of construction, and in the combination and arrangement of parts may be resorted to without departing from the spirit or scope of the invention as hereinafter claimed or sacrificing any of its advantages.

Having thus described our invention, what 85 we claim as new is:

In an aeroplane, a fuselage, a lower wing structure including a pair of sections projecting laterally from the fuselage one to each side thereof, struts rising from the sections, an upper wing structure on the struts across the top of the fuselage, a pair of planes, means hinging the forward ends of the planes between the forward struts immediately 90 above the wing sections and adjacent their forward edges, said pair of planes being adapted to normally rest upon the top surfaces of the wing section and within the confines of their contours, and means for swinging 95 the planes to angular positions in respect to the wing sections.

In testimony whereof we affix our signatures.

WILLIAM JORDAN.
CHARLES S. NICHOLS.
